MEANS FOR PREVENTING ENTRAINMENT
OF LIQUID REFRIGERANT WITH REFRIG-
ERANT GASEdward R. Magnus, St. Louis, Mo., assignor to
Snowhill Manufacturing Company, St. Louis,
Mo., a corporation of Missouri

Application April 23, 1949, Serial No. 89,281

6 Claims. (Cl. 62—115)

1

This invention relates to certain new and useful improvements in refrigeration systems.

It is the primary object of the present invention to provide a refrigeration system having extremely high K factor and being otherwise extremely efficient in construction and operation.

It is a further object of the present invention to provide a refrigeration system which is economical in cost of construction, maintenance, and operation.

It is a further object of the present invention to provide a refrigeration system having unique means for preventing entrainment of liquid refrigerant with the expanded refrigerant gas returning to the compressor.

It is also an object of the present invention to provide a refrigeration system of the type stated having means to prevent accidental flooding of the expansion chamber or compartment with liquid refrigerant.

With the above and other objects in view, my invention resides in the novel features of form, construction, arrangement, and combination of parts presently described and pointed out in the claims.

In the accompanying drawing:

Figure 1 is a diagrammatic view of a refrigeration system constructed in accordance with and embodying the present invention;

Figure 2 is a fragmentary vertical sectional view of a modified form of sump constructed in accordance with and embodying the present invention; and

Figure 3 is a schematic view of a refrigeration system illustrating more particularly the application of the present invention to a plate type cooler.

Broadly speaking the present invention resides in a refrigeration system consisting of a suitable evaporator provided with or connected to a sump-like tank vessel or chamber which is adapted to receive liquid refrigerant under pressure directly from a conventional condenser-compressor system. The influx of liquid refrigerant is controlled by a suitable expansion valve, so that the liquid refrigerant is cooled and the flash gas, resulting from its entry into the sump-like chamber, is returned to the suction side of the compressor. The cold liquid refrigerant from the sump-like chamber is pumped up to a header which is a part of a heat exchange unit in which the cooling effect is achieved. The liquid refrigerant is distributed from the header over the heat exchange surfaces in a continuously mov-

2

ing unbroken film having substantial mass and a certain portion of the liquid refrigerant will evaporate from the surface of the film, the remaining volume of the liquid flowing back into the sump-like chamber. An auxiliary refrigeration coil with separate temperature controls is located between the cooler and the sump, so that this region of the system is maintained at a lower temperature than the temperature of the gaseous refrigerant in the cooler, and insures complete condensation of any gas which may be entrained with the liquid flowing back into the sump, so that all possibility of gaseous entrainment or vapor locking is effectively prevented.

Referring now more specifically and by reference characters to the drawing, 1 designates a horizontal type shell and tube cooler provided at its ends with vertical tube sheets 2 for supporting a nest of spaced horizontal heat exchange tubes 3 opening at their opposite ends to tube-chambers 4 enclosed by conventional drum heads 5, the latter being provided with conduit pipes 6 through which the fluid to be cooled may be pumped into and withdrawn from the chambers 4 and thus caused to flow through the tubes 3. Enclosed within the shell 1 between the tube sheets 2 is an evaporator space 7 and in the upper region thereof is a horizontally extending refrigerant distribution header 8 provided with a plurality of spaced apertures 9 through which the refrigerant may descend in a shower over the surfaces of the tubes 3.

Suitably mounted beneath the shell 1 is a sump vessel 10 connected to the shell 1 by a vertical pipe 11 being of a relatively large diameter and having a hand control valve 12. The pipe 11 opens at its lower end into the upper end of the sump vessel 10 and at its upper end into the evaporator space 7 preferably at the low point of the shell 1 so that liquid refrigerant collecting in the bottom of the shell 1 will flow by gravity through the pipe 11 into the sump vessel 10. Leading from a conventional condenser C is a liquid refrigerant line 13 provided with a hand control valve 14 and communicating through a conventional float valve 15 to the lower interior portion of the sump vessel 10. The condenser C is conventionally connected to a compressor D. Leading out of the lower portion of the sump vessel 10 preferably on the opposite side with respect to the float valve 15 is a refrigerant recirculation line 16 having a hand control valve 17 and being connected to the intake side of a refrigerant recirculation pump 18 which in turn 55 discharges into a refrigerant line 19, the latter

being provided with a hand control valve 20 and being connected to the upper portion of the shell 1 so as to discharge liquid refrigerant onto the distribution header 9.

Mounted in and extending through the upper portion of one of the tube sheets 2 below the level of the distribution header 9 is a gas return line 21 connected through a hand control valve 22 to the intake side of the compressor D. Similarly, leading out of the upper end of the sump vessel 10 is an auxiliary gas return line 23 connected through a hand control valve 24 to the gas return line 21 outwardly of the hand control valve 22.

Disposed in heat exchange relationship around the pipe 11 below the hand control valve 12 and also preferably, though not necessarily, around the external walls of the sump vessel 10 is an auxiliary expansion coil 25 which is connected at its intake side through an expansion valve 26 and hand control valve 27 to the condenser C and at its other end the expansion coil 25 is connected through a gas return line 28 and hand control valve 29 to the intake side of the compressor D.

In operation, liquid refrigerant enters the sump vessel 10 through the float valve 15 maintaining a predetermined level of refrigerant in the sump vessel 10. The flash gas which is generated as the refrigerant enters the sump vessel 10 is drawn back through the compressor through the gas return line 23. The liquid refrigerant is circulated by the pump in substantial volume to the distribution header 9 and is caused to flow downwardly in very substantial volume over the heat exchange tubes 3 so as to maintain a downwardly flowing continuous and unbroken film which moves over the heat exchange surfaces at substantially high velocity. The excess liquid refrigerant collects in the bottom of the shell 1 and flows downwardly through the pipe 11 into the sump vessel 10 for recirculation by the pump 18.

The expansion valve 26 is set so that the expansion coil 25 will maintain the pipe 11 and the upper portion of the sump vessel 10 at a substantially lower temperature than the temperature of the return gas flowing out of the top of the shell 1 through the gas return line 21 thereby immediately condensing any gas particles which may be entrained with the return flow of liquid refrigerant or may for any other reason tend to collect in the pipe 11 and the upper portion of the sump vessel 10, thus eliminating any danger of flow back of liquid refrigerant through the gas return lines 21, 23, and preventing any vapor lock condition from being set up to interfere with or reduce the efficiency of the operation of the system.

If desired it is possible to provide a modified form of sump vessel 10', as shown in Figure 2, which is substantially identical in every respect with the previously described sump vessel 10 except that the external expansion coil 25 is eliminated and instead the sump vessel 10' is provided in one of its side walls with a relatively large opening 30 which is covered by a suitably gasketed and sealed closure plate 31. Mounted on the closure plate 31 and extending inwardly through the upper gas space 32 of the sump vessel 10' is an expansion coil 33 having a vertical loop 34 extending axially upwardly into the liquid refrigerant return pipe 11'. The coil 33 extends through the plate 31 by means of sealed-in connections 35, 36, and is conventionally connected to the condenser-compressor system (not shown).

The modified form of sump vessel 10' operates substantially in the same manner as previously described in connection with the sump vessel 10. The coil 33 is in this instance also maintained at a lower temperature than the temperature of the return gas in the refrigeration system and the returning liquid which flows downwardly through the pipe 11' cascades over the coil 33 and its upwardly extending loop 34 so that any entrained gases will be condensed. The coil 33, furthermore, functions to condense any relatively warm gases which might tend to collect in the upper portion of the sump vessel 10'.

If desired the present invention may be applied to or used in connection with a plate type cooler 37, as shown in Figure 3, in which the sump vessel 10, identical in every respect with the previously described sump vessel 10, is connected by a refrigerant supply line 38 and a refrigerant return line 39 to the plate cooler 37. This system is provided with only one gas return line 40 which is connected through a hand controlled valve 41 to the upper portion of the sump vessel 10. In this type of installation the sump vessel 10 is again provided with an auxiliary cooling coil 25 which is controlled by an expansion valve 26 set in such a manner as to maintain the desired temperature differential for the purposes heretofore described.

It should be understood that changes and modifications in the form, construction, arrangement, and combination of the several parts of the refrigeration system may be made and substituted for those herein shown and described without departing from the nature and principle of my invention.

Having thus described my invention, what I claim and desire to secure by Letters Patent is:

1. A refrigeration system comprising a compressor, a condenser operatively connected to the compressor, an evaporator operatively connected to the suction side of the compressor and having a sump, connection means for connecting the upper end of the sump to the evaporator, means for introducing liquid refrigerant from the condenser to the sump, means for circulating the liquid refrigerant from the sump to the evaporator, and auxiliary means located in heat exchange relation to the connection means for creating a cold zone between the evaporator and the lower portion of the sump, the temperature of which is substantially lower than the temperature of the gaseous refrigerant returning to the compressor from the evaporator.

2. A refrigeration system comprising a compressor, a condenser operatively connected to the compressor, an evaporator operatively connected to the suction side of the compressor and having a sump connection means for connecting the upper end of the sump and the evaporator, a float valve for introducing liquid refrigerant from the condenser to the sump, means for circulating the liquid refrigerant from the sump to the evaporator, and auxiliary means located in heat exchange relation to the connection means for creating a cold zone between the evaporator and the lower portion of the sump, the temperature of which is substantially lower than the temperature of the gaseous refrigerant returning to the compressor from the evaporator.

3. A refrigeration system comprising a compressor, a condenser operatively connected to the compressor, an evaporator operatively connected to the suction side of the compressor and having a sump connection means for connecting the upper end of the sump and the evaporator, means

for introducing liquid refrigerant from the condenser to the sump, means for circulating the liquid refrigerant from the sump to the evaporator, and an auxiliary evaporator coil located in heat exchange relation to the connection means for creating a cold zone between the evaporator and the lower portion of the sump, the temperature of which is substantially lower than the temperature of the gaseous refrigerant returning to the compressor from the evaporator.

4. A refrigeration system comprising a compressor, a condenser operatively connected to the compressor, an evaporator operatively connected to the suction side of the compressor and having a sump, means for introducing liquid refrigerant from the condenser to the sump, means for circulating the liquid refrigerant from the sump to the evaporator, and an auxiliary evaporator mounted in heat exchange relation to the sump and connected to the condenser for creating a cold zone, the temperature of which is substantially lower than the temperature of the gaseous refrigerant returning to the compressor from the evaporator.

5. A refrigeration system comprising a compressor, a condenser operatively connected to the compressor, an evaporator operatively connected to the suction side of the compressor and having a sump, means for introducing liquid refrigerant from the condenser to the sump, means for circulating the liquid refrigerant from the sump to the evaporator, and an auxiliary evaporator

mounted in the upper portion of the sump and connected to the condenser for creating a cold zone, the temperature of which is substantially lower than the temperature of the gaseous refrigerant returning to the compressor from the evaporator.

6. A refrigeration system comprising a compressor, a condenser operatively connected to the compressor, an evaporator operatively connected to the suction side of the compressor, a sump vessel connected to and depending from the evaporator by a pipe, means for introducing liquid refrigerant from the condenser to the sump, means for circulating the liquid refrigerant from the sump to the evaporator, and an auxiliary evaporator coil disposed around the pipe for creating, between the evaporator and the sump, a cold zone, the temperature of which is substantially lower than the temperature of the gaseous refrigerant returning to the compressor from the evaporator.
